UNITED STATES PATENT OFFICE.

ALLEN T. REED, OF BYERS, TEXAS.

LUGGAGE-CARRIER.

1,141,004.

Specification of Letters Patent. Patented May 25, 1915.

Application filed February 27, 1915. Serial No. 11,079.

To all whom it may concern:

Be it known that I, ALLEN T. REED, a citizen of the United States, residing at Byers, in the county of Clay and State of Texas, have invented certain new and useful Improvements in Luggage-Carriers; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in luggage carriers for automobiles and the object in view is to produce a simple and efficient device of this nature designed to be attached to the running board of the vehicle and affording means for holding a grip or other baggage.

My invention comprises various details of construction, combinations and arrangements of parts which will be hereinafter fully described, shown in the accompanying drawings and then specifically defined in the appended claim.

I illustrate the invention in the accompanying drawings, in which:

Figure 1 is a perspective view showing the application of my invention, and Fig. 2 is an enlarged detail perspective view of the device detached from the running board.

Reference now being had to the details of the drawings by letter, A, A designate two angle irons, each of which has at its lower end a curved-shaped clamp carrying member B carrying a clamp C which cooperates with the member to hold the irons upon the running board of an automobile. Fastened

to each angle iron is a bar D at right angles thereto and which bars serve as an extensible means for the device and which are clamped frictionally intermediate the two plates F and H, a suitable thumb screw 45 I passing through the two plates and adapted to hold the same in clamping relation with said bars. It will be noted that the bar F is longer than the bar H and affords means for preventing the object being carried from passing between the angle irons 50 A. Projecting at right angles from each angle iron is a bar N and in a plane at right angles to the bars D and which serve to hold objects from moving lengthwise of the foot 55 board.

By the provision of an apparatus embodying the features of my invention, it will be noted that a simple and efficient means is afforded whereby objects may be 60 conveniently carried upon the running boards of automobiles, the parts being adapted for use with various size packages to be carried.

What I claim to be new is:—

A luggage carrier for automobiles comprising upright members and means for fastening the same to the running board of an automobile, bars projecting toward each other from said members, clamping plates 70 adapted to engage said bars, a thumb screw engaging the plates, and other bars projecting from said members.

In testimony whereof I hereunto affix my signature in presence of two witnesses.

ALLEN T. REED.
